UNITED STATES PATENT OFFICE.

SIGMUND V. HUBER, OF PITTSBURG, PENNSYLVANIA.

SHEARING-MACHINE.

SPECIFICATION forming part of Letters Patent No. 724,010, dated March 31, 1903.

Application filed April 29, 1902. Serial No. 105,146. (No model.)

To all whom it may concern:

Be it known that I, SIGMUND V. HUBER, a citizen of the United States, residing at Pittsburgh, in the county of Allegheny and State 5 of Pennsylvania, have invented or discovered certain new and useful Improvements in Shearing Mechanism, of which improvements the following is a specification.

The invention described herein relates to 10 certain improvements in shear mechanism designed especially for cutting large sections.

Downcut shears, while presenting comparatively few difficulties to their manufacture, are objectionable in use, for the reason 15 that the feed-tables whereby the article is transferred to the shear must be so arranged that the upper edge of the lower shear-blade is below a plane tangential to the upper surfaces of the feed-rolls in order that the article 20 may be fed over such shear-blade. When the upper blade descends in such a form of shear mechanism, the article must be forced down onto the lower blade, and in so doing it is bent or distorted over the feed-roller. Up- 25 cut shear mechanisms have been constructed with stationary upper shear-blocks, which must be arranged a distance above the feed mechanism a little greater than the thickest piece to be cut. Hence in cutting their sec- 30 tions the article would be lifted from the feed-table by the upward movement of the lower shear-block, and if the article is hot a bending or distortion thereof will occur.

The invention described herein relates to 35 certain improvements in shearing apparatus, including the shearing and feeding elements, wherein provision is made by the adjustment of one of said elements to prevent any distorting or bending movement being imparted 40 to the article operated on during the shearing operation, and hence no bending or distortion of the article is liable to occur.

In general terms the invention consists in the construction and combination of parts 45 substantially hereinafter more fully described and claimed.

In the accompanying drawings, forming a part of this specification, Figure 1 is a front elevation of my improved shear mechanism. 50 Fig. 2 is a section elevation on a plane indicated by the line II II, Fig. 1. Fig. 3 is a section elevation on a plane indicated by the

line III III, Fig. 2. Fig. 4 is a horizontal section on a plane indicated by the line IV IV, Fig. 1. Fig. 5 is a similar view on a plane 55 indicated by the line V V, Fig. 1; and Fig. 6 is a sectional detail view through the upper shear cross-head and presser-block. Fig. 7 is a sectional elevation illustrating a construction wherein the shearing mechanism is 60 made adjustable relative to the feed-table. Fig. 8 is a sectional elevation of the construction shown in Fig. 7, the plane of section being indicated by the line VIII VIII, Fig. 7; and Fig. 9 is a view, partly in section and 65 partly in elevation, illustrating a further modification of my improvement.

In the construction shown in Figs. 1 to 6, inclusive, the shear mechanism consists of a bed-plate 1, to which are secured vertical 70 posts or uprights 2. On the upper ends of these uprights is secured a head-block 3, having formed thereon a ram 4 for the fluid-pressure cylinder formed in a cross-head 6, having its ends connected by rods 7 to the ends 75 of the lower cross-head 8, carrying the shear-blade 9. The ends of this lower cross-head 8 are arranged within suitable guideways formed in the inner faces of the posts or standards 2. When water is admitted into the 80 chamber in the piston 4, the pressure is exerted against the upper or closed end of the cylinder 5 in the cross-head 6, forcing the latter upward, and with it the cross-head 8 and shear-blade 9. The upper or shear blade 10 85 is secured to a block or cross-head 11, having its ends arranged in the guides in the posts or standards 2. This cross-head is supported vertically by means of fluid-pressure cylinders 12, in which a constant pressure is main- 90 tained. A suitable means for connecting the cross-head 11 with the rams or pistons 13 of the cylinders 12 consists of heads 14, carried by the upper ends of the pistons and having their ends connected, by means of rods 15, to 95 bars 16, pivotally connected to the cross-head 11, as clearly shown in Figs. 1 and 2. These cylinders are so proportioned and the pressure so regulated as to firmly support or hold the cross-head 11 against the adjusting-screws 100 17, screwing through nuts 18 in the block 3 and having worm-wheels 19 so keyed to the stems of the screws that the latter will rotate with the worm-wheels, but move freely lon-

gitudinally through the same. These worm-wheels 19 are rotated by means of worms 20, formed on shafts 21, provided at their outer ends with beveled pinions intermeshing with 5 corresponding pinions on the shaft 22, which can be rotated by hand or any suitable form or construction of motor. By the rotation of this shaft the cross-head 11 can be forced down or permitted to rise through the operation 10 of the fluid-pressure cylinders 12 as required by the thickness of the cross-section to be cut. This construction forms a quick and easy means for the adjustment of the cross-head 11 and shear-blade 10 to close proximity 15 to the upper surface of the article resting upon suitable supports, as the rollers of the feed mechanism A, so that there will be little lifting of the article on the rise of the lower cross-head 8 and shear-blade 9. It is 20 preferred to employ in connection with the upper cross-head a pressing and stripper block 23, which is mounted in suitable guide-ways formed on the cross-head 11. This presser-block is held in its lowered position, 25 but with freedom to rise as it is forced up by the article being sheared, by means of a rod 24, passing up through the block 23 and having its upper end exposed to the pressure of fluid within the piston 4, so that the presser-block will always be yieldingly held in contact 30 with the article during the shearing operation. In order to prevent the presser-block from dropping out of the guides, lugs 26 are so formed on the cross-head 11 as to 35 engage when the presser-block is in its lowered position shoulders 27 on the inner face of the presser-block, as shown in Figs. 2, 5, and 6.

In lieu of the construction shown in Figs. 40 1 to 6, wherein the upper or relatively stationary shear-blade is made adjustable with reference to the feed-table, the entire shear mechanism may be made adjustable with reference to the feed-table or supporting device, 45 or the feed-table or article-supporting device may be made adjustable with reference to the upper or stationary shear-blade. A desirable construction embodying the modification wherein the whole shear mechanism is 50 made adjustable is shown in Figs. 7 and 8 and consists of a carrying-block 28, supported by posts or pillars 29 through the medium of nuts 30, arranged within slots or recesses in the carrying-block and engaging threads 55 on the posts or pillars. The perimeters of the nuts are made in the form of worm-wheels and are adapted to be rotated by worms on shafts 31, which in turn are rotated through suitably-interposed gearing by a suitable 60 power mechanism, as the motor 32, mounted on the carrying-block. The posts or pillars are secured to foundation-blocks 33, which are provided with guide-grooves for the reception of wings on the lower or movable 65 cross-head 8^a, carrying shear-blade 9^a. The cross-head or lower shear-block 8^a is connected by rods 7^a to the cross-head 6^a, provided

with a ram 4, adapted to operate in the cylinder formed in the carrying-block 28. The blocks 33 are preferably formed integral 70 with a connecting-web 34, which serves as a support for the lower cross-head 8^a when in its lowest position.

In the constructions shown in Figs. 1 to 8 the feed mechanism or other support and the 75 shearing mechanism are so constructed and arranged that the edge of the lower shear-blade will be normally below the plane of the feed or supporting mechanism, so that the article to be sheared will pass easily over 80 such blade. When the upper shear-block is adjusted up or down according to the thickness of the article to be sheared, the lower cross-head or shear-block 8 will not be shifted, as the ram 4 is free to change its position 85 in its cylinder. Hence the length of stroke of the lower shear-block will vary in accordance with the thickness of the article to be sheared, thereby effecting a considerable saving of time and operating fluid. 90

As before stated, the support or mechanism for feeding the article may be made adjustable relative to the upper shear-blade. A convenient construction to this end is shown in Fig. 9 and consists of a frame 35, 95 provided with bearings for the feed-rollers 36. The vertical adjustment of this table can be effected in any suitable manner—as, for example, by means of nuts 37, mounted on the threaded rods 38, which, projecting into sleeves 39 in the frame 35, serve as guides for the latter. The peripheries of the nuts 37 on which the frame rests are toothed to engage worms on the shafts 40, so connected by suitable gearing as to rotate in unison to raise 105 and lower the table. By suitably adjusting the feed-table the upper surface of the article to be sheared can be brought into or 110 nearly into contact with the upper shear-blade, so that there will not be any material lifting of the article by the lower shear-blade when forced up to shear the article. The 115 shearing mechanism can be of any suitable or desirable construction of the upcut type. In the construction shown the lower shear-block 8^a is connected by rods 7^a to the upper cross-head 6^a, having the ram 4 formed integral therewith. The cylinder is formed in the stationary head-block 3, to which the upper shear-blade is also secured in any suitable 120 manner. 125

I claim herein as my invention—

1. A shear mechanism having in combination an elevated head-block, a lifting cross-head arranged above said block, a fluid-pressure mechanism arranged between said block and cross-head and a movable shear-block arranged below the head-block and connected to the lifting cross-head, substantially as set forth. 130

2. A shear mechanism having in combination a block carrying the upper shear-blade, a lifting cross-head arranged above said block, a lower movable shear-block connected

- to the lifting cross-head, and means for vertically adjusting the block carrying the upper shear-blade, substantially as set forth.
3. A shear mechanism having in combination an elevated head-block, a lifting cross-head arranged above said block, a fluid-pressure mechanism interposed between said block and cross-head, a movable shear-block arranged below the head-block and connected to the lifting cross-head and an adjustable shear-block arranged between the head-block and lower shear-block, substantially as set forth.
4. A shear mechanism having in combination an elevated head-block having a ram or piston formed thereon, a lifting cross-head arranged above said block and provided with a cylinder for the reception of said ram or piston, a movable shear-block arranged below the head-block and connected to the lifting cross-head and an upper shear-block arranged between the head-block and the lower shear-block, substantially as set forth.
5. A shear mechanism having in combination an elevated head-block, a lifting cross-head arranged above said block, a fluid-pressure mechanism interposed between said block and the cross-head, a movable shear-
- block arranged below the head-block and connected to the lifting cross-head, an upper shear-block arranged between the head-block and lower shear-block, a presser-block mounted on the upper shear-block and means for holding the presser-block yieldingly as against the upward movement, substantially as set forth.
6. A shear mechanism, having in combination an elevated head-block, a lifting cross-head arranged above said block, a fluid-pressure mechanism interposed between said block and cross-head, a movable shear-block arranged below the head-block and connected to the lifting cross-head, an upper shear-block arranged between the head-block and lower shear-block, fluid-pressure mechanism for vertically supporting the upper shear-block, and mechanism for forcing down the upper shear-block against such fluid-pressure mechanism, substantially as set forth.

In testimony whereof I have hereunto set my hand.

SIGMUND V. HUBER.
